SURFACE CONTROLLED COMBINATION
PUMP AND GAS LIFT

Granville A. Humason, Houston, Tex., assignor
of fifty per cent to Ben H. Johnston, and
twenty-five per cent to Earl L. Lester, Sr., both
of Houston, Tex.

Application December 13, 1941, Serial No. 422,833

14 Claims. (Cl. 103—10)

This invention relates to a combination pump and gas lift for oil wells and more particularly to a device which may be utilized for initially producing a well under formation pressure and thereafter continuing production of the well by gas lift and/or pumping action after the formation pressures have fallen to a value where natural flow ceases.

The primary object of the invention is to provide a construction for efficiently producing earth fluids from a well bore.

Another object is to provide a device through which a well may be produced under natural formation pressures.

Still another object is to provide a device of the class described in which natural formation pressure may be supplemented by a pressure fluid lift operation.

A further object is to utilize both pressure fluid and pump operations in producing a well.

A still further object is to provide a device which may also be utilized as a pump alone for producing a well.

The foregoing objects, together with further objects, will be more fully apparent from the following description taken in connection with the accompanying drawings in which:

Fig. 1 is an elevational view of a well head including the tube actuating mechanism;

Figs. 2 and 3 are enlarged successive views of the well head with parts shown in section to more clearly illustrate the structure thereof;

Figs. 4, 5 and 6 are successive vertical sectional views of a portion of the device within the well bore;

Fig. 7 is a sectional view taken on the line 7—7 in Fig. 5;

Fig. 8 is a sectional view taken on the line 8—8 in Fig. 5;

Figs. 9, 10 and 11 are successive vertical sections of an alternative embodiment of the portion of the device positioned within the well bore;

Fig. 12 is a sectional view through an alternative form of the gas admission element of the device;

Fig. 13 is a sectional view through a well head showing the manner of removing the flow string from the well in accordance with the invention;

Fig. 14 is a sectional view of a sealing flange which may be used at the well head to provide a seal between the flow string and the casing.

In Fig. 1 there is shown a casing 1 within a well bore and having a well head 2 attached thereto at its upper end. The well head includes a recip-

rocable head 3 adapted to move vertically and hence move the flow string 4 to a desired elevated position or to reciprocate such string to effect combined aeration and pumping action as hereinafter disclosed.

Considering Figs. 4, 5 and 6 in seriatim, it is to be noted that the casing 1 extends downwardly within the well and is provided proximate its lower end with openings 5 to admit formation fluids thereto from surrounding formations. Within the lower end of the casing 1 is positioned a plunger assembly, generally identified as 6, provided intermediate its ends with a seal or packer 7 which forms a seal with the casing and hence 15 divides the casing into upper and lower annular chambers 8 and 9 so that formation fluids entering the openings 5 must pass through the plunger assembly and also that a pressure fluid may be applied in the casing 1 and about the flow tube 4 above the packer 7.

Referring more specifically to the complete structure just generally described, it is to be noted that the casing head 2 (Figs. 2 and 3) comprises a flanged member 10 having one or more openings 11 to admit pressure fluid to the chamber 8. The member 10 is surmounted by a flanged outlet member 15, there being a seal ring 12 interposed between these members. A downwardly extending tail pipe 16 is attached to the member 15 and lipped seal ring 13 fits within the upper end of the annular space between the tail pipe and the member 10. This lipped seal ring hence serves to supplement the seal ring 12 and also to prevent any leakage through the threads 14 between the tail pipe 16 and the outlet member 15.

There is a slidable seal 17 between the tail pipe 16 and the flow string 4 so that well fluids elevated within the flow string may pass through the openings 18 above the seal 17 (Fig. 3) and thence upwardly to be discharged through the outlet 19.

A flanged nipple 20 is bolted to the member 15 and is provided with side slots 21 to receive studs 22 attached to slips 23 so that the latter may be releasably positioned into or out of engagement with the flow tube 4 as, for example, when removing the flow tube from the well as illustrated in Fig. 13.

In order to prevent upward leakage of well fluids above the outlet 19 and about the slips 23, a ring 25 carrying the lipped seal ring 26 is positioned about the tube 4 and held in place by the nipple 20.

Attached to the upper flange of the nipple 20

is a base member 30 having an annular passage-way 31 therein communicating with inlets 32 through which is conducted an operating fluid to pass upwardly in the stems 33 which serve as pistons within the cylinders formed by the tubular members 34 threadedly secured in openings in the lower face of the head 35. This head has a central opening to receive the tube 4 and this opening is flared at 36 to receive slips 37 which cooperate with the upper slips 38 so that the tube 4 is positively gripped and may be forced either upwardly or downwardly.

The upper slips 38 are forced downwardly by a collar 39 which is engaged by the ring nut 40 threadedly attached to the upper end of the head 35. Guide rods 41 are attached to the base 30 and slidably pass through openings in the flanged portion of the head 35.

It seems apparent that the application of the pressure fluid through the openings 32 to the base 30 may be utilized to position the head 35 at any desired elevation or, if desired, and as contemplated in one mode of operation, may be utilized to effect reciprocation of the flow string 4.

As already pointed out, fluids rising in the flow string 4 pass through the openings 18 and thence upwardly and outwardly through the outlets 19. There are circumstances under which it is desirable to close these openings so that the well is maintained positively closed and for this purpose there is provided a cylindrical valve member 50 (Fig. 3) fitting slidably within the upper end of the flow tube 4. The lower end of this member is adapted to engage an annular shoulder 51 when it is forced downwardly in the flow tube 4. The downward movement of the valve member 50 is effected by pressure introduced through the inlet 52 in the cap member 53 attached to the upper end of the flow string 4. When such pressure is relieved the member 50 is moved upwardly and is held in its uppermost position by fluids rising under pressure within the flow string 4.

Above the plunger assembly 6, the flow string 4 is provided with a traveling valve 60 from which a barrel 61 extends downwardly and is interiorly engaged by series of cups 62 and 63 surrounding the stem 64 which extends upwardly from the packer 7. The collar 65 which forms a coupling between portions of the stem 64 has projections 66 on its lower end to engage with the complementary recesses in the flange 67 at the lower end of the barrel 61. This feature provides a non-rotatable connection between the flow string 4 and the plunger assembly when the flow string is lifted. Hence, it is possible to rotate the complete assembly by merely lifting and rotating the flow string.

Additional spaced series of cups 68 and 69 surround the stem 64 below the cups 63 and the intermediate connector 70 in the stem is provided with a plurality of passages 71 so that well fluids can pass upwardly within the assembly past a series of pressure fluid openings 72 which communicate with the bore of a stand pipe 73 terminating at its upper end in an upwardly opening check valve 74 having a bonnet portion 75 provided with a plurality of openings 76 to effectively inject the gaseous aerating fluid to the well fluids passing upwardly thereabout.

It is to be noted that the barrel 61 is provided with a plurality of openings 77 proximate its lower end so that pressure fluid within the chamber 8 will be admitted through such openings to the passages 72 when the flow string and barrel assembly are elevated sufficiently that the openings

77 are moved into mating relation with the passages 72.

Beneath the packer 7 is provided a standing valve assembly which includes an upwardly opening check valve 80 which, similar to the valve 74, is provided with a bonnet having a plurality of openings 76'. This valve is designed to admit formation gases to the interior of the plunger assembly, and to this end there is provided a stand pipe 81 about the valve so that any fluids entering the valve must enter the upper end of such stand pipe and thus pass through the radial passages 82 to the bore of the stem 83 upon which the valve 80 is mounted.

15 The coupling member 84 to which the valve 80 is attached is also provided with bypass passages 85 to conduct well liquid upwardly thereabout. Attached to the lower end of the coupling 85 is a second standing valve 90 below which is 20 provided a foraminated plug 91 so that formation fluids entering the passages 5 may pass upwardly through the standing valve. The plug 91 engages a supporting projection 92 in the bottom of the casing 1 so that the position of the 25 plunger assembly 6 is determined.

The operation of the structure as thus far described is believed apparent from the description. For the sake of illustration, it will be assumed that the various parts are in the relative positions 30 shown in Figs. 1 to 6, inclusive. Under these circumstances adequate formation pressure will cause well fluids to rise to the surface and tend to move the valve member 50 upwardly. If pressure is removed from the inlet 52, this valve member will move upwardly and the well will flow under normal formation pressure.

If, however, the formation pressures have fallen sufficiently that additional effort is necessary to flow the well, the head 3 may be elevated so 40 that the openings 77 and 72 are brought into mating relation, whereupon pressure fluid applied to the chamber 8 will enter the flow string and assist in elevating and removing the fluids from the well. Under certain circumstances it is desirable to supplement such gas lift action, and in such case fluid applied to the inlet 32 is applied intermittently so that the head 3 and the associated structure are reciprocated whereby 45 aeration of the column of fluids in the flow string 50 is effected during a portion of the stroke.

When, however, the barrel 61 moves downwardly sufficiently that the openings 77 pass below the cups 68, the admission of gas is terminated and the traveling valve 60 opens during such movement. The succeeding upstroke lifts the fluids above the traveling valve 60 and also causes formation fluids to rise through the standing valve 90 about the aeration valve 80. In event gas pressure has accumulated about the 55 packer 7 there will also be the admission of such gas through the valve 80 whereby aeration of the rising column of fluid will take place.

It seems apparent that the reciprocation of the head 35 may be so controlled that the openings 77 will not be uncovered, in which case pure 60 pumping action takes place, there being only such aeration of the produced fluids as takes place from the admission of gas through the valve 80 accumulating beneath the packer 7.

70 The device of the invention as shown in Figs. 9, 10 and 11 of the drawings includes parts that are the same as those of the structure thus far described and are identified by the same reference characters. In this embodiment it is to 75 be noted that the packer 7' comprises a pack-

ing ring 100 positioned within a recess within the connector 101 and is adapted to engage the shoulder 102 in the casing 1 whereby the elevation of the plunger assembly is determined.

The structure extending downwardly from the packer 7' is identical to that heretofore described except that the aeration valve located below the packer is of the type shown at 74 in Fig. 4.

The standing valve 103 is mounted above the packer 7' and serves to prevent any downward movement of well fluids which have been admitted through the valve 90 and aerated by the gas accumulating beneath the packer 7' and admitted through the valve 80'.

The bore of the stand pipe 73' communicates directly with the bore above the standing valve 103, while the annular space 104 about this stand pipe communicates with the exterior of the assembly through the openings 72'. By means of this construction the pressure fluid entering through the openings 71, when such openings are moved into substantially mating relation with the passages 72', passes upwardly through the space 104 and thence through the passages 105 in the head 106 at the upper end of the assembly. Accordingly, the admitted aerating fluid completely surrounds the upwardly rising column of well fluids and more effectively completes the aeration whereby the fluid rises through the standing valve 60 into the flow string 4.

It is, of course, understood that, as previously explained, this construction can be utilized to permit a well to flow under formation pressure. The flow string 4 may be moved to such a position that gas lift is effected or, if desired, a combination gas lift and pumping action may be utilized.

In Fig. 12 the upper end of the plunger assembly is shown as being modified by providing a special coupling 110 between the series of cups 63 and 68, and such coupling is provided with a plurality of upwardly and inwardly inclined passageways 111 so that pressure fluid admitted through the openings 71 in the barrel 61 and thence through the passages 111 is traveling in a generally upward direction as it enters the fluid column interiorly of the plunger assembly.

Fig. 13 illustrates the manner of removing the flow string 4 from within the well. It is to be noted that the entire upper portion of the casing head assembly above the flanged nipple 20 has been removed and that the slips 23 have been released for movement by removal of the studs 22. Also, the ring 25 and its associated lipped seal ring 26 have been removed inasmuch as the ring 25 is provided with ears which are adapted to move downwardly through internal slots in the flanged nipple 20 and thence be rotated in the undercut groove so that this assembly will be held in position. It is therefore possible to remove this sealing assembly without removal of the flanged nipple 20. The slips 23 may therefore be used in a conventional manner during the lifting and removal of sections of pipe from the flow string 4.

Fig. 13 also illustrates diagrammatically the direction of flow of various fluids at the well head. The produced fluids are exhausted through the passage 19 to a separator 112 whence the separated liquids are withdrawn in a manner well known in the art. The gaseous constituents however, are conducted through a pipeline

113 to a pump 114 and thence to the pressure fluid inlet 11 so that such fluids may be utilized to assist in the lifting of well fluids within the flow string.

6 For the purpose of circulating fluid through the well at any time, the invention also comprehends an assembly such as that shown at 115 in Fig. 14, this assembly being adapted to fit about the pipe 4 and to replace that portion of the well head assembly which surmounts the member 10.

The assembly 115 comprises a flange member 116 having outlets 117. Above the outlets 117 the structure is substantially the same as that

15 shown at the upper end of the reciprocable head 3. Comparable elements are identified by primed reference characters. In the stead of slips within the chamber formed by the members 116, 39' and 40', there is provided a seal-off member 118 of rubber or other suitable sealing material. This seal-off member converges in opposite directions from the center, and hence increasing or decreasing sealing effect may be produced by tightening or loosening the ring nut 40'. It seems apparent that by the use of this construction it is possible to provide an effective seal about the flow tube 4 so that circulation may be effected therebelow without leakage about the flow tube. At the same time, 30 the structure is such that, if desired, reciprocatory, rotational or axial movement of the flow tube may be effected.

Broadly, the invention comprehends a combination pump and gas lift for oil wells which is capable of efficiently producing such wells.

35 What is claimed is:

1. A well flowing device comprising a flow tube, means for reciprocating said flow tube, a traveling valve in said tube, means comprising a 40 relatively reciprocable plunger and barrel, said barrel being operable by said flow tube to effect pumping action on fluid therein, and means for admitting a pressure fluid to said flow tube during a portion of the reciprocatory movement thereof.

2. A well flowing device comprising a flow tube, means for reciprocating said flow tube, a traveling valve in said tube, means comprising a relatively reciprocable plunger and barrel, said 50 barrel being operable by said flow tube to effect pumping action on fluid therein, and means operable when the flow tube is reciprocated within predetermined limits for admitting a pressure fluid to the flow tube to supplement the pumping action by aeration of the fluids within the tube.

3. A well flowing device including a casing, a plunger assembly therein, a seal between the assembly and casing in the well, a reciprocable flow tube surrounding the assembly above said seal, an upwardly opening valve in said flow tube, means at the well head for reciprocating the flow tube to effect pumping action upon fluid admitted to the tube from the plunger assembly, and means for admitting pressure fluid from the 60 casing to the flow tube during a portion of the stroke.

4. In a device of the class described, a casing, a plunger assembly therein, a standing valve in said assembly, a seal between said assembly and casing forming upper and lower chambers, a flow string extending into the casing and communicating with the bore in said assembly, said flow string and assembly having relatively reciprocable telescoping portions a standpipe surrounding said assembly below the seal, and an

aerating valve in the assembly communicating with the standpipe to aerate with accumulated gas the liquids rising within the assembly below the seal.

5. In a well flowing device, a casing, a plunger assembly, a seal between the casing and assembly, valve means for admitting well fluids to the assembly below the seal, a flow tube telescopically surrounding the assembly above the seal, and spaced seals between said assembly and tube, there being passages through the walls of said tube and additional passages to the interior of the assembly intermediate the spaced seals to admit pressure fluid to the well fluids when the tube is moved to a predetermined position relative to the assembly.

6. A well flowing device comprising a flow tube, a check valve therein, a stationary plunger extending into said tube, a passage for admitting well fluids upwardly through the plunger to the interior of the tube, and means for admitting an aerating fluid to the well fluids when the tube is moved to a predetermined position relative to the assembly.

7. A well flowing device comprising a flow tube, a check valve therein, a stationary plunger extending into said tube, a passage for admitting well fluids upwardly through the plunger to the interior of the tube, and means for admitting an aerating fluid to the well fluids when the tube is moved to a predetermined position relative to the assembly, said last mentioned means including an aerating head having divergently upwardly extending passages to discharge the aerating fluid throughout the body of well fluids moving upwardly through the plunger.

8. In a device of the class described, a casing-head, a flow tube extending upwardly therefrom, a base on said head, tubular members extending upwardly therefrom, a movable head surrounding the flow tube and releasably attached thereto, cylinders on said head extending telescopically downwardly about said tubular members, and means for supplying a pressure fluid to the interior of said members to elevate the head and tube.

9. In a device of the class described, a casing-head, a flow tube passing therethrough, a base on said head, a movable head surrounding the flow tube above said base, said movable head including slips engaging the tube and restraining from relative upward or downward movement

between the head and tube, and means for periodically lifting said head.

10. In a device of the class described, a casing-head, a base thereon, a flow tube passing through said head and base, a movable head surrounding the flow tube above said base, upwardly and downwardly engaging slips in said head, means for clamping and releasing said slips, and a piston and cylinder mechanism interposed between the base and head to periodically lifting the head and flow tube.

11. In a device of the class described, a casing head, a flow tube passing therethrough, an outlet member attached to said head, a tail pipe attached to said member and extending downwardly therefrom about the flow tube, and seal means between the flow tube and tail pipe, there being openings in the flow tube above said seal means so that fluids from the flow tube pass 20 through the tail pipe and outlet member.

12. In a device of the class described a casing-head, an outlet member attached to said head, a flow tube passing through said head and member, a tail pipe surrounding said flow tube and attached to said member, a lipped ring sealing the space between the flow tube and casinghead, and seal means between the tail pipe and flow tube, there being openings in the flow tube above 25 said seal means to admit fluid from the flow tube to the outlet member.

13. In a well flowing and pumping mechanism, a casing, a flow tube therein including a traveling barrel, a plunger assembly including a plurality of cups having sealing engagement with the exterior of said barrel, means for effecting a pumping action when said flow tube is reciprocated relative to said assembly, and means for admitting a pressure fluid to the flow tube when the flow tube is moved to a predetermined position relative to the assembly.

14. In a device of the class described, a casing-head, an outlet member attached to said head, a flow tube passing through said head and member, a tail pipe attached to said member and surrounding said flow tube, seal means between said flow tube and tail pipe providing relative reciprocation of said tube and pipe, there being openings in the flow tube above said seal means to admit fluid from the flow tube to the outlet member, and valve means movable within the flow tube to close said openings.

GRANVILLE A. HUMASON.
